UNITED STATES PATENT OFFICE.

EDMUND PYNE, OF MORRISANIA, NEW YORK, ASSIGNOR TO BIGELOW CARPET COMPANY, OF WORCESTER, MASSACHUSETTS.

DESIGN FOR A CARPET-PATTERN.

Specification forming part of Design No. 5,482, dated January 23, 1872.

Specification describing a new and original Design for a Carpet, invented by EDMUND PYNE, of Morrisania, in the county of Westchester and State of New York.

The accompanying photographic illustration represents my new design. This invention relates to a new configuration of three center figures A, B, and C, and of the intermediate scroll D of a carpet, and is fully represented in the photograph. Each of the three center figures, it will be seen, constitutes a separate design, and the scroll also is of novel and ornamental outline.

I claim as my invention—

1. The design for the center figure A, as shown.
2. The design for the center figure B, as shown.
3. The design for the center figure C, as shown.
4. The design for the scroll D, as shown.

EDMUND PYNE.
